UNITED STATES PATENT OFFICE.

HENRY S. HALE, OF PHILADELPHIA, PENNSYLVANIA, ASSIGNOR TO THE HALE AND KILBURN MANUFACTURING COMPANY, OF PHILADELPHIA, PENNSYLVANIA, A CORPORATION OF PENNSYLVANIA.

CUSHION.

No. 884,730.

Specification of Letters Patent.

Patented April 14, 1908.

Application filed September 12, 1906. Serial No. 334,294.

To all whom it may concern:

Be it known that I, HENRY S. HALE, a citizen of the United States, residing at Philadelphia, in the county of Philadelphia and 5 State of Pennsylvania, have invented certain new and useful Improvements in Cushions, of which the following is a specification.

This invention concerns cushions, and has reference, more particularly, to cushions for 10 use as seats and backs of car-seats. In order that these cushions may be as nearly fire-proof as possible, the parts thereof have heretofore been made of metal with the exception only of the covering material. A rectangular frame of sheet-metal has been employed having metallic slats extending across between opposite sides thereof on which are mounted spiral springs which serve to yieldingly support the covering material. On account of the use of metallic parts, considerable difficulty has been experienced in securing 20 the covering material to the frame.

The object of my invention is to provide a simple, inexpensive and convenient means 25 by which this can be done.

In accordance with the invention, I unite with the metallic frame of the cushion, strips of suitable material into which tacks may be driven to hold the edge of the covering material of the cushion firmly to the frame. Strips of fiber or paper may be used for this purpose, but preferably, I employ strips of wood, and in order that these may be rendered non-inflammable, I impregnate them 35 with a suitable fireproofing compound and also I incase them in sheet-metal, this casing having holes therein through which the tacks for holding the covering material to the frame may be driven into the wooden strips. As 40 thus constructed, the covering material may be drawn down tightly over the surface of the cushion and its edges tacked to the wooden strips forming part of the cushion frame, the holes through the metallic casing 45 of the strips being made large so that no difficulty is experienced by the workmen in finding them with the tacks. The cushion is none the less fireproof on account of the use of the wooden strips, since these are not only 50 rendered non-inflammable by the compound with which they are impregnated but are entirely incased in metal.

The preferred embodiment of my invention is illustrated in the accompanying drawings, in which

Figure 1 is a top view of a cushion broken away and sectioned in part, Fig. 2 is a section showing one edge of the cushion, and Fig. 3 is a perspective view of the incased tacking strip.

Referring to these drawings, the frame 1 of the cushion is of rectangular shape, consisting of four frame-sections secured together at their ends. Each section consists of two sheet-metal frame-members secured together 60 at their edges and bent intermediate the edges to provide open space between the opposite sides of the section, thus contributing great strength to the frame. In Fig. 2 the frame-section is shown as consisting of a member 2 bent lengthwise thereof to form three sides of a rectangle and having outwardly turned flanges 3 at the lateral edges. The other member 4 of the section is a flat, sheet-metal strip having folds 5 at its lateral edges adapted to incase the flanges 3 to secure the two frame-members together. Rivets may be provided in the flanges thus formed to prevent relative longitudinal movement of the members of a frame-section. Extending 65 across between the opposite sides of the frame are channeled, metallic slats 6 secured at their ends to the flanges on the frame-sections. Mounted on the frame and on the slats 6 are a plurality of spiral springs 7 arranged in lines across the frame, and these support on their upper ends a plurality of flat, sheet-metal springs 8. The covering material of the cushion may be of any suitable construction; I have shown it as consisting of a coarse inner covering 9, usually termed the "first canvas", extending down at its edges to the frame 1, over this a piece of heavy felt 19 and a filling of hair or other upholstery material 20, and over these the 70 outer covering 11. With the outer covering 11 may be associated a sheet of muslin 10; the edges of both of these extending down over the sides of the cushion to the bottom of the frame.

The edges of the first canvas and the outer covering are secured to the frame of the cushion in the following manner. United to the frame-sections so as to extend entirely around the edge of the frame 1, are strips to 105 which the edges of the covering material are tacked. In Fig. 3, I have illustrated the construction of the strip which I prefer to employ. The strip itself is indicated by the numeral 12, and may be of fiber, paper or 110

other material, but is preferably of wood and is impregnated with a suitable fireproofing compound. The strip, thus prepared, is incased in a sheath 13 of sheet-metal extending around three sides of the strip 12, and this sheath has a series of holes 14 cut therein on each of two sides, the holes of one series being staggered relatively to those of the other. Also, holes are provided through the strip and its sheathing to receive bolts 15 by which the strip is secured to the frame 1. A strip, thus prepared and cut to suitable length, is secured to each of the frame-sections between the outer side thereof and the outwardly extending flange on that side, the side of the strip 12 not covered by the sheath 13 lying against the flange. In this position the strip is secured by bolts 15 extending through the strip and flange and nuts 16 thereon.

In assembling the cushion, the edges of the first canvas 10 are drawn down tightly and tacked to the side of the tacking strip 12 by tacks 17 extending through the holes 14 in the casing 13. The holes in the casing are made large so that the workmen will have no difficulty in finding them with the tacks. The felt 19 and hair 20 are then positioned upon the first canvas and the muslin 10 and outer covering 11 are then drawn down over them. The edges of the muslin may be tacked to the side of the strips 12 if desired; preferably, however, the edges of the muslin and outer covering are drawn down tightly over the first canvas together, carried under the tacking strips 12 and secured to the strips by tacks 18 extending through the holes 14 in the casing 13 at the bottom thereof. The covering material of the cushion is thus firmly secured to the frame in a simple, convenient and inexpensive manner and, though strips of wood are provided to which the covering is tacked, these strips cannot burn as they are both fireproofed and incased in metal.

What I claim as new and desire to secure by Letters Patent of the United States is:—

1. In a cushion, the combination of a metallic frame consisting of sheet-metal frame-sections united at their ends, each of said sections having a flange extending outwardly of the frame from the upper edge of the section, a strip secured to each frame-section with two of its faces against the outer side of the section and the under side of the flange thereon, a metallic casing secured to each strip and protecting the other faces thereof, springs supported on the frame, a covering yieldingly positioned by said springs, its edges being carried under said strips, and tacks extending through the edges of the covering and openings in said casings and into the under sides of said strips to secure the covering to the frame, substantially as described.

2. In a cushion, the combination of a me-

tallic frame consisting of sheet-metal frame-sections united at their ends, each of said sections having a flange extending outwardly of the frame from the upper edge of the section, tacking strips, bolts securing each of said strips to the flange on a frame-section with one face against the under side of the flange and another against the outer side of the frame-section, a metallic casing secured to each strip and protecting the other faces thereof, springs supported on the frame, a covering yieldingly supported by said springs, its edges being carried under said strips, and tacks extending through the edges of the covering and openings in said casings and into the under side of said strips to secure the covering to the frame, substantially as described.

3. In a cushion, the combination of a metallic frame consisting of sheet-metal frame-sections united at their ends, each of said sections having a flange extending outwardly of the frame from the upper edge of the section, a strip secured to each frame-section with two of its faces against the outer side of the section and the under side of the flange thereon, a metallic casing secured to each strip and protecting the other faces thereof, springs supported on the frame, two coverings yieldingly supported by said springs, tacks securing the edges of the inner covering to the outer faces of said strips and tacks securing the edges of the outer covering to the under side of the strips, said tacks extending through openings in said casings, substantially as described.

4. In a cushion, the combination of a metallic frame consisting of sheet-metal frame-sections united at their ends, each of said sections having a flange extending outwardly of the frame from the upper edge of the section, a strip secured to each frame-section with two of its faces against the outer side of the section and the under side of the flange thereon, a metallic casing secured to each strip and protecting the other faces thereof, springs supported on the frame, a covering yieldingly positioned by said springs, and tacks extending through the edges of the covering and openings in said casings and into said strips to secure the covering to the frame, substantially as described.

5. In a cushion, the combination of a metallic frame consisting of sheet-metal frame-sections united at their ends, each of said sections consisting of two sheet-metal strips, one bent longitudinally to form three sides of a rectangle in cross-section and to provide flanges at the lateral edges, and the other bent to form folds at the lateral edges inclosing said flanges, one of said flanges and its inclosing fold forming a flange extending outwardly of the frame, a strip secured to each frame-section with two of its faces against the outer side of the section and the under side of the flange thereon, a metallic casing secured to each strip and protecting the other faces thereof, springs supported on the frame, a covering yieldingly positioned by said springs, its edges being carried under said strips, and tacks extending through the edges of the covering and openings in said casings and into the under sides of said strips to secure the covering to the frame, substantially as described.

under side of the flange thereon, springs supported on the frame, a covering yieldingly positioned by said springs and tacks extending through the edges of the covering and 5 openings in said casings and into said strips to secure the covering to the frame, substantially as described.

This specification signed and witnessed this fifth day of September, 1906.

HENRY S. HALE.
